UNITED STATES PATENT OFFICE.

JOE MIHALINEC, OF MENLO PARK, CALIFORNIA.

T-SQUARE.

1,287,072.

Specification of Letters Patent. Patented Dec. 10, 1918.

Application filed March 19, 1918. Serial No. 223,324.

To all whom it may concern:

Be it known that I, JOE MIHALINEC, a citizen of the United States, residing at Menlo Park, in the county of San Mateo and State of California, have invented new and useful Improvements in T-Squares, of which the following is a specification.

This invention relates to T-squares such as are generally used by draftsmen, the object in view being to produce a satisfactory, reliable and accurate device of the character referred to embodying in connection with a main body or blade, and a head, novel means for permitting said members to be adjusted in angular relation to each other and firmly clamped when the desired angular adjustment has been obtained.

The invention consists of the features of construction, combination and arrangement of parts, hereinafter fully described and claimed, reference being had to the accompanying drawing, in which:

Figure 1 is a plan view of the improved T-square.

Fig. 2 is an enlarged vertical section on the line 2—2 of Fig. 1, looking in the direction of the arrows.

Fig. 3 is a horizontal section on the line 3—3 of Fig. 2.

Fig. 4 is a transverse vertical section on line 4—4 of Fig. 2.

Fig. 5 is a similar view on line 5—5 of Fig. 1.

The improved T-square comprises the main body or blade 1 and the T-head 2. The parts 1 and 2 may be constructed of any desired or preferred dimensions according to the particular use to which the device is to be applied.

The blade 1 is formed at the opposite edges thereof with ribs 3 and graduated strips 4 are secured to the opposite lateral edges of the blade 1, said strips being formed with grooves 5 in the inner edges thereof to receive and tightly fit the ribs 3. In the preferred embodiment of the invention, one of the graduated strips contains the English measurements while the other strips contain measurements in the metric system.

Adjacent to one end the blade 1 is formed with a generally round opening or observation orifice 6, said opening being of such shape as to provide an inwardly extending gage point 7 of triangular formation described on an angle of about 30°. (The ex-

treme point of the gage 7 lies directly in the center of the arc on which the greater portion of said opening is described. Between the opening 6 and the adjacent extremity of the blade 1, the latter is formed with a transversely extending groove or seat 8 in which is secured a strip 9. Extending from the center of said strip 9 through a hole formed by a ferrule 10, fastened to the T-head proper is a pivot stud 11 having at the opposite end thereof a disk-shaped head 12 secured to the stud or pivot 11 by a screw 13 or the equivalent thereof. The object of the construction just described will herein-after appear.

Secured to the inner edge of the head 2 is a facing strip 14 adapted to rest against the edge of the drawing board in connection with which the T-square is used. Extending along the opposite outer edge of the head 2 and around the ends thereof is a binding strip 15 of metal, the same in width as the thickness of the body of the head 2. The opposite outer corners of the head are beveled as shown at 16 and the strip 15 extends around and protects such beveled corners. The strip 15 also extends across the opposite ends of the head 2 and the extremities of said strip are bent inwardly to form retaining fingers 17 which are inlaid in the body of the head. Arranged centrally of the strip 15 and extending inwardly therefrom is a comparatively thin and generally arcuate gage strip 18 which is graduated in degrees as indicated at 19 in order to enable a definite angular relation to be obtained between the blade 1 and the head 2. One end portion of the strip 15 is inwardly offset to form a depressed part 20 which is designed for the reception of the milled head 21 of a clamping screw 22; the head 21 being seated flush in the depressed part 20 of the binding strip 15. The inner end portion of the clamping screw 22 is threaded as shown at 23 and is inserted through a stationary nut 24 having inwardly projecting parallel guides or flanges 25. Mounted for sliding movement between the guides 25 is a head 26 of a clamp 27 having a concaved clamping edge 28 designed to bear against the pivot stud 11 so as to prevent any relative movement between the blade 1 and the head 2. By loosening the screw 22, the clamping action between the member 21 and the pivot 11 or stud 11 is relieved, enabling the head 2 to be adjusted into a new angular relation to

the blade 1. The arc of the gage strip 18 is such that the outer edge of said strip registers with the extreme tip of the gage point 7 as shown in Fig. 1.

5 Having thus fully described my invention, I claim:

1. In a T-square, the combination of a blade, a head having a pivotal relation to said blade, a pivot stud carried by one of 10 said members, a clamping screw extending lengthwise of said head and operable at one extremity of the head, a stationary nut through which the inner end portion of said screw is threaded, guiding means forming 15 part of and projecting from said nut, and a clamping member for coöperation with said stud, said clamping member being slidably related to said guiding means and adapted for actuation by said clamping screw.
- 20 2. In a T-square, the combination of a blade, a head having a pivotal relation to said blade, a pivot stud carried by one of said members, a clamping screw extending lengthwise of said head and operable at one 25 end of the head, a stationary nut through which the inner end portion of said screw is threaded, guiding means projecting from 30 said nut, a clamping member for coöperation with said stud, said clamping member being slidably related to said guiding means and adapted for actuation by said clamping screw, said blade being formed with an ob- 35 servation opening extending therethrough, a gage point extending to the center of said

opening, a binding strip secured to the marginal edge of the head, and an arcuate gage strip extending inwardly from and having a positive connection with said binding strip, said arcuate gage strip being graduated to register with said gage point.

3. In a T-square, the combination of a blade, a head having a pivotal relation to said blade, a pivot stud carried by one of said members, a clamping screw extending lengthwise of said head and operable at one 40 extremity of the head, a stationary nut through which the inner end portion of said screw is threaded, guiding means projecting from said nut, a clamping member for coöperation with said stud, said clamping member being slidably related to said guiding means and adapted for actuation by said clamping screw, said blade being formed with an observation opening extending therethrough, a gage point extending to the 45 center of said opening, a binding strip secured to the marginal edge of the head and having an offset portion received in a depression in one end of the head and adapted to receive the head of the clamping screw, 50 and an arcuate gage strip extending inwardly from and having a positive connection with said binding strip, said arcuate gage strip being inlaid in the head of the T-square and being graduated to register 55 with said gage point.

In testimony whereof I affix my signature.

JOE MIHALINEC.
